UNITED STATES PATENT OFFICE.

JOHN WALLACE TAYLOR, OF PHILADELPHIA, PENNSYLVANIA.

SAFETY DETONATING-FUSE.

1,321,407.

Specification of Letters Patent. Patented Nov. 11, 1919.

Application filed September 19, 1918. Serial No. 254,724.

To all whom it may concern:

Be it known that I, JOHN WALLACE TAYLOR, a citizen of the United States, and a resident of Philadelphia, in the county of Philadelphia and State of Pennsylvania, have invented certain new and useful Improvements in Safety Detonating-Fuses, of which the following is a specification.

My invention is an improvement in safety detonating fuses, and has for its object to provide mechanism in connection with the safety chamber of a detonating fuse for absorbing the explosive energy of the detonator to avoid the transmission of the explosion to the booster charge.

In the drawings:

Figure 1 is a vertical section of a shell showing one embodiment of the invention;

Figs. 2 and 3 are similar views, showing other embodiments;

Fig. 4 is a section on the line 4—4 of Fig. 3, looking in the direction of the arrows adjacent to the line;

Fig. 5 is a section on the line 5—5 of Fig. 1, looking in the direction of the arrows adjacent to the line.

As is known, detonating fuses frequently have a safety chamber in which the detonator is normally carried. If the detonator, which is naturally more or less liable to spontaneous action, should explode in this position during transportation or in the bore of the gun, no damage could result, other than the loss of the detonator. When the fuse is armed, which it is designed to be after being expelled from the gun, the detonator passes from the safety chamber into an exploding chamber in direct contact with the charge of the shell and then functions, properly exploding the shell on impact with the target. The safety chamber must be a relatively large chamber of adequate capacity to contain the gaseous products of combustion of the detonator at a nominally low pressure and temperature, sufficiently low to prevent rupture of the chamber or communication of the explosive to the shell charge. The present invention is designed to obtain the same results, without requiring the use of a large safety chamber.

In the embodiment of the invention shown in Fig. 1, the striker 1 carries the detonator 2, and the said striker is movable longitudinally in the closing cap 3 of the fuse stock 4, which is threaded into the small end of the shell indicated at 5. This fuse stock

has a chamber 6 at its inner end, which carries the booster charge, the inner end of the chamber being closed by the usual plug 7.

A casing 8 is arranged within the booster charge chamber, the open end of the casing 8 being in line with the striker and so arranged that the casing carrying the detonator charge will move into this casing 8 when the striker is moved inward, and the casing 8 carries a firing pin 9 for firing the detonator charge when the striker is driven inward to cause the casing 2 to engage with the pin 9. The striker is normally held from inward movement by a split ring consisting of similar sections 10, which encircle a reduced neck 11 on the striker the ring sections bearing at one end against the end of the fuse stock 3 and at the other against the annular shoulder formed between the body of the striker and the reduced portion. These ring sections are held in place by a light wire 12 which engages about them in an annular groove during the acceleration of the shell in the bore of the gun. When the shell leaves the gun, however, the ring sections are thrown apart by centrifugal force, leaving the striker free except for the shear wire 13 which extends transversely of the striker, engaging at its ends the fuse stock 3. On impact with the target, the striker breaks the shear wire and the detonator charge is carried back into the casing 8 and fired on the pin 9, detonating the booster charge in the booster chamber 6, which in turn explodes the shell charge.

The detonator charge casing 2, when in normal safety position, is within a small annular chamber 14, the said chamber being a safety chamber. This chamber opens to the atmosphere by substantially radial openings 15 and in case of premature explosion of the detonator the gases are distributed through these openings 15 to the atmosphere, preventing any disastrous results from following the premature action of the detonator.

In Fig. 2 the striker 16 carries the detonator casing 17 in the same manner as in Fig. 1, and the striker is held by the half rings 18 and the shear wire 19, the half rings 18 being bound by the light wire 20. The casing 21 is the same as the casing 9 and carries the firing pin 22 for firing the detonator charge. The fuse stock 23 carries the booster charge 24, and is closed by the usual cap 25. The safety chamber 26 is filled with a suitable reagent, capable of

absorbing the gases evolved by a premature explosion of the detonator, such, for instance, as charcoal, metallic sponge or cuprous chlorid. A catalytic substance, 5 such as pulverized nickel, may be added to hasten the chemical reaction if desired, or a substance may be used capable of combining with the gas to form a solid or liquid product, as, for instance, a metallic oxid or 10 hydro-oxid capable of forming a carbonate or other solids with carbon monoxid or other gases.

In Fig. 3 the striker 27 is held by the ring sections 28 bound by the light wire 29 and 15 by the shear wire 30 and the striker carries the detonator casing 31 which is adapted to be moved into the chamber 32 on impact, the said chamber carrying the firing pin 33. The fuse stock 34 and the cap 35 are 20 the same as in Figs. 1 and 2. The safety chamber 36 is a trifle larger than those shown in Figs. 1 and 2, and within this chamber is arranged an agent which, while not reducing the amount of effective gas 25 present after premature explosion of the detonator by chemical combination or physical absorption, yet reduces the temperature rapidly by means of its physical heat characteristics, as, for instance, quartz 30 sand or metallic wool. A preferable agent is copper cloth, since it presents an extensive exposed surface and has a very high heat conductivity as well as a high specific heat. Its heats of fusion and volatilization 35 are also high. The distortion of the wire mesh, the raising of its temperature and the fusion and even partial volatilization all require heat, which very rapidly reduces the temperature and pressure of the evolved 40 gases of the detonator explosion. As shown, a strip 37 of copper cloth is used, the said strip being wound in spiral form about the detonator casing and the adjacent end of the striker in the safety chamber.

With the improvement a large safety 45 chamber is not necessary, thus giving more space for the bursting charge of the shell and fuse and making the construction very flexible. In cases where it is not desirable to have openings into the safety chamber, 50 as, for instance, when firing into water or marshy ground, then the construction of Figs. 2 or 3 is preferable. When there are no objections to the openings 15 the form of Fig. 1 is both simple and effective. 55

If desired, a salt with its water of crystallization may also be added in the construction of Fig. 2 to assist the chemical reaction or even to extinguish the flame with the moisture evolved on heating. 60

I claim:

1. In detonating fuses having safety chambers encircling the detonator charge when in withdrawn position, means in connection with the said chamber for reducing 65 the pressure and temperature in the same in case of premature explosion of the detonator, said means comprising reagents capable of absorbing or combining with the products of combustion. 70

2. In detonating fuses having safety chambers encircling the detonator charge when in withdrawn position, means in connection with the said chamber for reducing the pressure and temperature in the 75 same in case of premature explosion of the detonator, said means comprising reagents capable of rapidly absorbing the heat generated by the premature explosion of the detonator. 80

3. In a detonating fuse having a safety chamber, means in the said chamber for reducing the pressure and temperature in the same in case of premature explosion of the detonator and consisting of material 85 capable of rapidly absorbing the heat generated by the premature explosion.

JOHN WALLACE TAYLOR.
